(57) **CLAIM**

The ornamental design for a tableted candy vending machine, as shown and described.

DESCRIPTION

A candy vending machine that processes powdered candy into tableted candy for dispensing in response to input by a user.

FIG. 1 is a front perspective view of the tableted candy vending machine;

FIG. 2 is a front elevational view of the tableted candy vending machine;

FIG. 3 is a rear elevational view of the tableted candy vending machine;

FIG. 4 is a left side elevational view of the tableted candy vending machine;

FIG. 5 is a right side elevational view of the tableted candy vending machine; and,

FIG. 6 is a top plan view of the tableted candy vending machine.

The broken line showing of environment is for illustrative purposes only and forms no part of the claimed design.
